UNITED STATES PATENT OFFICE

162,006

WHAT-NOT SHELF UNIT

Harry C. Carter, Middle River, Md.

Application December 22, 1949, Serial No. 6,793

Term of patent 14 years

(Cl. D33—3)

To all whom it may concern:

Be it known that I, Harry C. Carter, a citizen of the United States, residing at Middle River, Baltimore County, State of Maryland, have invented a new, original, and ornamental Design for What-Not Shelf Unit, of which the following is a specification, reference being had to the accompanying drawing, forming a part hereof.

I claim:

The ornamental design for a what-not shelf unit, as shown.

HARRY C. CARTER.
